SPINNING DEVICE

Ernest Lee Griggs, Jr., Waynesboro, and Emery Folger Taylor, Staunton, Va., assignors to E. I. du Pont de Nemours & Company, Wilmington, Del., a corporation of Delaware

Application October 11, 1949, Serial No. 120,742

9 Claims. (Cl. 34—82)

1

The invention relates to an improvement in apparatus for use in the production of filamentary structures. It relates to apparatus for separating a traveling filament or plurality thereof from a fluid surrounding it. More particularly, the present invention relates to an improved spinning cell exit door and aspiration take-off device useful in the manufacture of filaments from solutions of filament-forming materials by the dry-spinning or evaporative method.

In the conventional method for spinning filaments, as, for example, in using a volatile solvent and a cellulose ester or ether, the solution is extruded under considerable pressure through a spinneret provided with a plurality of orifices into a heated enclosure generally called a "spinning cell." An evaporative gaseous medium, for example, air, is passed through the spinning cell either co-currently or countercurrently to remove volatile solvents from the formed filaments. The filaments are then collected as a yarn of the desired denier in the usual manner. It has been customary to employ, particularly in the case of co-current air flow, a slot or hole in a cone-type enclosure at the bottom of the spinning cell for filament exit. Somewhat prior to passing through the slot or aperture, the filaments pass an aspiration screen through which the solvent-laden air is withdrawn from the spinning cell and sent to the solvent recovery system. The downward vertical flow of the air or other evaporative medium is thereby altered abruptly. In many cases the change may amount to 90°. In the area of sudden change in flow direction considerable turbulence occurs. This, of course, is detrimental, for it leads to broken filaments and yarns of inferior quality. In addition to the turbulence, a "pumping action" is set up, and an appreciable amount of solvent-laden air is carried out into the atmosphere. Not only is this economically wasteful, particularly in view of the progressively higher losses being experienced with increased spinning speeds, but it is a health hazard.

Filaments are also oftentimes led from the spinning cell through a side opening in the cell wall which may comprise simply a small hole. By an internally positioned thread guide the filaments are usually deflected at right angles from their normal downward path. In another system the velocity of the co-current air stream in the dry-spinning of cellulose acetate yarns is increased gradually during its downward passage through the cell by employment of a conical spinning tube having decreasing cross-sectional area. In such apparatus, however, the fila-

ments are drawn from the cell at right angles to the normal and are thereby placed under undue tension resulting in inferior articles of manufacture. Furthermore, there is a tendency for the downward flowing stream of air in the tube to carry the filaments beyond the side exit point.

No satisfactory apparatus has heretofore been designed which simultaneously reduces air turbulence in the thread path within the cell and minimizes the dragging of solvent-laden air into the spinning room. It has indeed long been a desideratum in the field of dry-spinning to have an apparatus designed so that the take-off for the solvent-laden air is so situated with respect to the thread exit point and of such a shape that little, if any, solvent-laden air is dragged into the spinning area.

It is an object of this invention to provide an improved apparatus of simple construction adapted for use with the usual type of dry-spinning cell, whereby the aspiration take-off is placed adjacent to the filament exit and arranged in such a manner that the evaporative medium sweeps across the downwardly flowing filaments as they are positioned together by the sides of the exit aperture or by guides positioned just prior to their exit from the cell. Another object of the present invention is to reduce the turbulence of the evaporative medium in the filament path within the cell without interfering with the convenient operation of the spinning cell. A further object is to reduce substantially the quantity of solvent being lost from the cell enclosure. A more specific object of the invention is to employ a throat insert or any restricted cross sectional arrangement to realize improved solvent recovery. A further object is to permit the yarn to leave the spinning cell enclosure through an aperture without being deflected from its normal downward path. A still further object is to provide a screen access door or "fluff" trap arrangement which is capable of being readily visible and easily removable for cleaning without interrupting the spinning. Another objective is to separate a traveling filament or the like from a fluid surrounding it. Still further objects are to minimize fire and health risks involved in the dry-spinning process, and to provide an effective means for keeping yarn, broken filaments and spinning dope from passing into the solvent recovery system. Other objects of the invention will appear hereinafter.

The above objects of this invention are accomplished by the provision of an aspiration take-off device positioned adjacent to the filament exit

and a simply constructed exit door arrangement so designed that a wedge or throat insert is placed in the enclosure just before the point at which the filaments leave the cell. The evaporative medium, preferably air, which is pulled down the cell by suction to a narrow throat or area of restricted cross-section, begins to change its direction as it passes over the filaments and then passes through a fine mesh screen into the suction header and solvent recovery system. The throat insert tends to increase further the air velocity across the filaments at the narrowest point of the cell, thereby giving a suction effect in addition to the suction being applied by the solvent recovery system. The thread guide which may be positioned close to the filament exit permits the bundle of filaments to be centered so that they may pass through the smallest allowable opening.

The apparatus provides a means for separating the traveling filament from the solution or vapor surrounding it as it passes through the device of this invention. The apparatus comprises a hollow, preferably cylindrical member, which is tapered somewhat at the exit end and in that end is a small orifice for the exit of the filament. Near this orifice or joined to it is a guide which serves to keep the filament running properly. Access to the orifice and guide is provided for by a conveniently hinged door opening into the device. At the tapered end is a vent through which the vapor or solvent passes. For better streamlining, this vent may extend below the filament exit but this design is not required. The passageway between the tapered end and the vent is made much smaller than either that of the tapered section or vent in order to enhance the suction through the filament exit into the device. This effect is attained by providing in the vent a restriction contiguous with the tapered section. Also in the vent is a screen and there is provided an access to this screen.

The invention will be more easily understood by reference to the following detailed description when taken in connection with the accompanying illustrations in which

Figure 1 is a side elevational view partly in section showing the aspiration type spinning cone and the exit door, taken on line 1—1 of Figure 2,

Figure 2 is a plan view, on line A—A of Figure 1, showing the exit opening in more detail and

Figure 3 is a perspective view of the apparatus of this invention showing the exit door and bottom trap door in the open position.

It is understood that the following description is given by way of example only and is in no respect limitative.

Referring to Figure 1 the lower portion of the spinning cell 1 adjoins the aspiration take-off exit door assembly 2. The cell and the spinning device 2 of this invention are attached by any convenient means. For example, gaskets 3 are used as seals and cap screws 4 are anchored in flanges 5. Any convenient anchoring means may, of course, be used.

The spinning cell may be heated in any desired manner and is provided with means (not shown) for passing a drying and evaporative medium, such as air, therethrough, for the purpose of removing as much as possible of the volatile solvent from the freshly formed yarns. The thread 6 passes through the spinning cell and aspiration device 2 of this invention in a downward direction, the evaporative medium flowing preferably co-currently therewith. The thread is then

5 withdrawn from the cell through aperture 7. Mounted in the device is a guide 9 for guiding the filament or yarn through the exit. This guide could be placed in the door 8 if desired and a plurality of guides could also be used. In any event the guide is so built and positioned with respect to the cell aperture 7 that the direction of air across the thread in the cell tends to hold the thread positioned in the guide. By means of throat insert 11 near the tapered section 12 and in the vent 18 or the aspiration take-off, a suction effect supplementary to that being applied by the solvent recovery system is achieved since the cross-sectional area through which the flowing evaporative medium passes is diminished, thereby increasing the velocity of the evaporative medium across the filaments just prior to their exit from the cell enclosure. By varying the type of throat insert 11 near 12 the Venturi effect may be varied so that at different volumes of gas (evaporative medium) flow, which are required in spinning at different denyards, the linear velocity across the thread and the suction effect at the thread outlet may be suitably varied. By changing the size of the "baffle" or insert 11 the area through which the gas flows can be changed to give whatever linear velocity is desired. The desired restriction in the vent 18 may, of course, be attained by shaping the vent as by indentations. It is preferred, however, to use separate inserts, for the fluid flow can be varied more at will using various inserts attached simply as shown in Figure 1. Further the inserts may be in other forms such as a bar attached to the door 8. All that is needed is a passageway connecting the tapered end section to the vent which passageway is smaller than the end section and vent.

Still referring to Figure 1, the evaporative medium is led into the cell enclosure through one or more openings at the upper part of the cell (not shown) and is withdrawn through screen 13 which is placed in the assembly so as to be easily removable therefrom and then via conduit 14 to the solvent recovery apparatus (not shown). Trap door 15 which is hinged at point 16 is maintained in its normal position by a retaining spring 17 and may be readily opened as soon as any accumulation of yarn, broken filaments, etc. are observed therein. This permits cleaning of the portion of the apparatus below the yarn exit point 7 without interrupting the spinning operation.

Referring to Figure 2, the guide 9 consists of, preferably, beveled corners on the polished slot or aperture 7. While other types of guides may be used it is preferred to position the guide as close as possible to the aperture. The slanting walls of 8, the flow of fluid in the unit across the filament, and the suction effects combine to keep the filament in the valley of the aperture. Although the drawing shows apparatus designed for single thread production, the invention may readily be adapted for double or multiple thread manufacture. In Figure 3, the exit door 8, riding 65 on hinges 10, and the trap door 15 are shown in the open, non-operating positions. The screen 13 is detachable and serves as a "fluff" trap. The solvent recovery line 14 is curved upward and to the right side of the cell but this line could be placed in any other convenient direction. Obviously, the recovery of the solvent is an operation entirely independent of this invention and may be achieved by any of the customary methods.

75 The enclosure of the aspiration take-off and

exit door assembly may be constructed of metal, such as iron, cast aluminum, or other materials not adversely affected by the volatile liquid to be recovered from the filaments. If thread guides are employed in the assembly, AlSiMag ones are recommended. The snug fitting, removable screen 13 may be constructed of metallic or fibrous materials, preferably 45 mesh, 0.008" thick brass screening is employed.

Although for convenience the invention has been described for use in co-current dry spinning processes, it is not to be implied that the apparatus hereinafter claimed is designed solely to cover the situation where the evaporative medium is moving in the direction of the filament flow, for the invention is also applicable to countercurrent dry spinning procedures.

In the spinning of cellulose acetate from acetone solutions, the evaporative medium is preferably air containing acetone picked up in the process and is introduced by suitable aspiration at a rate of from 11-18 cu. ft./per minute per wind-up position. The necessary control of the rate of passage of the evaporative medium may be secured with suitable flowmeters and/or orifices in a known fashion. The enclosure surrounding the exit of the yarn may vary somewhat from that in the above discussed drawings. It is preferred, of course, that the enclosure have a smoothly curved assembly as shown rather than any angular contour, since stagnant corners are thereby avoided to a large extent. It is necessary, however, to employ a tapering type of arrangement in order to create the desired suction. A thread guide may be positioned close to the opening through which the filaments pass from the enclosure into the atmosphere.

With the present day emphasis on increased spinning speeds, particularly in the case of the dry-spinning of cellulose acetate yarn, the greater has been the tendency, in heretofore known devices, for the solvent-laden air to be dragged into the atmosphere. When using conventional aspiration take-off devices and single thread cone doors the acetone concentration of the air being dragged from the cell at a point 1" below the thread exit opening was about 30 grams/cubic meter. With the design of the present invention the acetone concentration of the air at a point 1" below the thread exit opening was about 4 grams/cubic meter or about the same as the room average in the neighborhood as measured by a standard acetone meter. This indicates that a substantial reduction in the amount of solvent being carried into the spinning room has been achieved by the device of this invention. By reducing the cross section at position 12 in the cell enclosure, the velocity of the evaporative medium is increased with a resultant drop in pressure, thereby creating a suction (ca. 0.33 inch water vacuum) and permitting air to flow from the room into the cell through the aperture rather than in the reverse direction, thereby minimizing solvent loss.

The invention is useful in the production of any filaments, synthetic or natural. Although the apparatus has been described primarily in connection with the dry-spinning of acetone-soluble cellulose acetate from an acetone solution, the invention is also applicable to the dry-spinning of cellulose acetate of the same or different combined acetic acid content dissolved in any one or more of the well-known volatile solvents for cellulose acetate. Also, other cellulose organic esters and ethers may be spun into yarn from a

suitable solution of volatile solvents utilizing the apparatus hereinafter claimed. For instance, yarns of cellulose propionate, cellulose butyrate, cellulose acetate propionate, cellulose acetate butyrate, etc. may be produced. The apparatus may also be used in conjunction with the manufacture of yarns from condensation products of cellulose and glycols or other polyhydric alcohols or other materials that are capable of being formed into filaments by evaporative or dry-spinning methods. The volatile solvent employed in the above-mentioned cases may be any volatile one in which said material is soluble, for example, methyl ethyl ketone, methyl alcohol, ethyl alcohol, ethylene glycol, methylene chloride, ethylene chloride, propylene chloride, methyl acetate, ethyl acetate, ethyl lactate, ethyl alpha-hydroxybutyrate, dioxane, diacetone alcohol, chloroform, tetrachloroethane or similar chlorinated hydrocarbons of mixtures thereof with small amounts of alcohol. The device may also be used in the handling of other filaments such as those from polyamides, polyacrylonitriles, polyvinylchlorides and the like. It may be readily adapted for the handling of yarns, wires, rods, tubing and, in general, of any continuous filamentary structure. The structure need not be freshly formed. The apparatus may be used, for example, in removing water from a preformed filament. The device can be used, in general, for separating a traveling filament from a fluid.

The present invention has particular utility in preventing the loss of solvent from the cell enclosure through the aperture by which the rapidly traveling yarn passes to the wind-up. Obviously the higher the speed of the filament travel, the greater will be the percentage of volatile solvent carried out into the atmosphere, other conditions remaining constant. By use of the apparatus hereinabove described high speed spinning may be employed with minimum acetone losses. Working conditions are also made safer and more healthful, since the acetone concentration in the spinning area is kept well below the maximum human exposure concentration of 4.84 grams/cubic meter (2,000 p. p. m. by volume) for a daily 8-hour exposure set by the American Standards Association Committee on Toxic Vapors, Dust and Gases.

The apparatus also has the advantage of being easily cleaned and of benefiting spinning by minimizing conditions causing filament breaks, as for example, by improving thread alignment. Thus, by the employment of this apparatus high speed spinning of yarn by the dry-spinning process is made more economically feasible and yarns of improved quality are produced due to diminution of air turbulence within the spinning cell.

Any departure from the procedure described herein which conforms to the principles of the invention is intended to be included within the scope of the claims below.

We claim:

1. Apparatus for separating a traveling filament from a fluid which comprises a hollow member having a tapered end section; in that section an exit for said filament; and a vent for the exit of said fluid connected to said section by a passageway containing a constriction so that said passageway is smaller than said section and said vent.

2. Apparatus for separating a traveling filament from a fluid which comprises a hollow cylindrical member having a tapered end section; in that section an exit for said filament; and a

vent for said fluid connected to said section by a passageway containing a constriction so that said passageway is smaller than said section and said vent.

3. Apparatus for separating a traveling filament from a fluid which comprises a hollow, cylindrical member having a tapered end section; in that section an exit for said filament in a plane parallel to the long axis of said member; and a vent for the exit of said fluid connected to said section by a passageway containing a constriction so that said passageway is smaller than said section and said vent.

4. Apparatus for separating a traveling filament from a fluid which comprises a hollow, cylindrical member having a tapered end section; a door opening into said section; in said section an exit for said filament; and a vent for the exit of said fluid connected to said section by a passageway containing a constriction so that said passageway is smaller than said section and said vent.

5. Apparatus for separating a traveling filament from a fluid which comprises a hollow, cylindrical member having a tapered end section; a door opening into said section; in said section an exit for said filament; a guide for said filament to said exit; and a vent for the exit of said fluid connected to said section by a passageway containing a constriction so that said passageway is smaller than said section and said vent, said vent extending below said filament exit.

6. Apparatus for separating a traveling filament from a fluid which comprises a hollow, cylindrical member having a tapered end section; a door opening into said section; in said section an exit for said filament; a guide for said filament to said exit; and a vent for said fluid connected to said section by a passageway containing a constriction so that said passageway is smaller than said section and said vent, said vent extending below said filament exit; and a screen in said vent.

7. Apparatus for separating a traveling filament from a fluid which comprises a hollow, cylindrical member having a tapered end section;

5 a door opening into said section; in said section an exit for said filament; a guide for said filament to said exit; a vent for said fluid connected to said section by a passageway containing a constriction so that said passageway is smaller than said section and said vent, said vent extending below said filament exit; a screen in said vent; and an access in said vent to said screen.

10 8. Apparatus for separating a traveling filament from a fluid which comprises a hollow member having a tapered end section; in that section an exit for said filament; a vent for the exit of said fluid extending below said filament exit; and a restriction in said vent contiguous with said tapered section for enhancing the suction through said filament exit into said member.

15 9. Apparatus for separating a traveling cellulose acetate filament from an evaporating medium which comprises a hollow member having a tapered end section; in that section an exit for said filament; a vent for the exit of said evaporating medium; a passageway connecting said vent to said tapered end section; in said passageway a constriction making said passageway smaller than said section and said vent; a screen in said vent; a door opening into said tapered end section; and an access in said vent to said screen.
